Primary Examiner — Karen S Acker

(57) **CLAIM**

The ornamental design for a board spacer, as shown and described.

DESCRIPTION

FIG. 1.1 is an upper perspective view of a board spacer according to the invention.

FIG. 1.2 is a lower perspective view thereof.

FIG. 1.3 is a front elevational view thereof.

FIG. 1.4 is a rear elevational view thereof.

FIG. 1.5 is a top plan view thereof.

FIG. 1.6 is a bottom plan view thereof.

FIG. 1.7 is a left side elevational view thereof.

FIG. 1.8 is a right side elevational view thereof.

FIG. 1.9 is a cross-sectional view thereof, taken in the direction of the dashed line shown in FIG. 1.5.

FIG. 1.10 is a cross-sectional view thereof, taken in the direction of the dashed line shown in FIG. 1.4.
